UNITED STATES PATENT OFFICE.

GEORGE W. CROSS, OF CARBONDALE, PENNSYLVANIA.

SCREEN.

SPECIFICATION forming part of Letters Patent No. 645,072, dated March 13, 1900.

Application filed August 4, 1898. Serial No. 687,680. (No model.)

To all whom it may concern:

Be it known that I, GEORGE W. CROSS, a citizen of the United States, residing at Carbondale, in the county of Lackawanna and 5 State of Pennsylvania, have invented a certain new and useful Improvement in Screens, of which the following is a specification.

This invention relates to the perforated surfaces of screens designed for the separation 10 of coal and other material into predetermined sizes. Particularly the invention concerns that type of screening-surface known in the art as "crimped," and consisting generally of a continuous jacket or integral segments, the 15 interstices, preferably quadrilateral in form, being surrounded by webs, to which, or to certain of which, various curvatures are given, raising them above or depressing them below the working surface of the screen. In 20 the construction of segments or jackets of this type two important considerations are present. The first of these is that the surface should attain maximum efficiency in the separating operation—that is to say, the coal 25 or other material in its passage through the screen must be subjected to such action by the screening-surface as to facilitate the passage of the material through the perforations, provided the particles are of the size intended 30 to pass therethrough. The other consideration referred to is that the surface as a whole must present maximum strength to withstand the action of the coal or other material passing through the screen. In many screens 35 heretofore devised the second consideration has been sacrificed to the first. In other words, in attempting to attain the maximum degree of efficiency in the separating operation the screening-surface as a whole has 40 been weakened to such an extent as to give way after certain of the webs bounding the interstices have been worn, both by the action of the material passing through the screen and by corrosion, &c.

45 The object of the present invention is to satisfactorily meet both requirements above stated, and, moreover, to do this by the provision of a screening-surface which may be readily and therefore cheaply crimped or otherwise fashioned by any convenient means—such, for instance, as by dies or rollers.

The invention is illustrated in the accompanying drawings, in which—

Figure 1 is a plan view of a screen-segment embodying my improvement. Fig. 2 is a 55 transverse section on the line 2 2 of Fig. 1. Fig. 3 is a transverse section on the line 3 3 of Fig. 1, and Fig. 4 is a longitudinal section on the line 4 4 of Fig. 1.

Referring to the drawings, in which similar letters of reference denote corresponding parts, it will be seen that the invention is disclosed as embodied in a segment rather than in a continuous jacket, such as above referred to, and that this segment consists of a sheet 60 of steel or other suitable material, the perforations therein being so arranged as to leave side margins a a' and end margins a^2 a^3 . This construction, while not imperative, is desirable on account of the added strength of 65 the segment. The margins may be provided with the usual bolt-holes to provide for the attachment of the segment to a revoluble screen. One or more of the edges or margins of the plate may also be provided with tumblers or other appliances of any desired description. Such tumblers or other appliances forming no part of the present invention are 70 not illustrated herein.

Referring now to the interstices b in the 75 segment, these, as will be seen, are substantially quadrilateral in form, the corners being slightly rounding, rather than angular, to prevent weakening the webs. Each of the interstices b is bounded by two transverse 80 webs c and c' and by two longitudinal webs d and d' .

After the plate has been provided with the perforations described certain of the webs thereof are crimped or curved in the following manner: The alternate webs, both transverse and longitudinal, are made sinuous in form in such manner as that at one junction e the transverse webs shall be elevated, while at the next adjacent junction f the web is depressed or left in the original plane of the sheet. The same is true of the undulating longitudinal webs, one junction g of each of such webs being elevated, while at the next adjacent junction h the web is depressed or 90 left in the plane of the sheet. This operation, 95 repeated over the entire surface of the seg-

ment, leaves a number of junctions between transverse and longitudinal webs which are elevated above the original plane of the plate, each of which junctions, together with the 5 webs extending outwardly therefrom in the longitude and the latitude of the segment, separates four adjacent and substantially quadrilateral interstices, while all of the 10 eight junctions with which those longitudinally and transversely extending webs are connected remain in the original plane of the 15 plate.

Due to the construction above described the coal or other material in its passage 20 through the revolving screen will be prevented from sliding over the surface of the segment or jacket, but will, on the contrary, be continuously turned over or "tumbled" or otherwise agitated by the projecting webs 25 and junctions which extend inwardly toward the axis of the screen. More than this, such particles of material as are of the proper size to pass through the perforations are guided to the perforations and their passage there-through assured. In attaining this result I 30 am able by means of the construction described to dispense entirely with sharp curvatures of the webs bounding the interstices, which curvatures have a tendency to weaken the screening-surface. Thus instead of crimping or curving inwardly or outwardly one web bounding one side of that interstice the only 35 curvature of the webs of the present construction is that of two contiguous webs, together with the intermediate junction. The curvatures, therefore, in the screen-surface herein shown and described are of relatively greater size than those heretofore employed, and therefore necessarily more gradual. 40 Added to this is the fact that where, for instance, a longitudinal web is curved inwardly

toward the axis of the screen it is met midway by a correspondingly-curved transverse web and the whole are united by an elevated junction, which receives the weight of the 45 coal and adds greatly to the strength and rigidity of the segment.

Although I have described my present invention as applied to a screen-segment, it is obvious that the same might equally well be 50 utilized in continuous jackets for revoluble screens such as have heretofore been employed in this art.

Having now described my invention, what I claim, and desire to secure by Letters Patent, is—

1. An integral screen-surface provided with substantially-quadrilateral interstices, four of said interstices being bounded by webs lying in substantially the same plane but 60 separated from each other by webs extending above that plane, substantially as set forth.

2. An integral screen-surface having substantially-quadrilateral interstices, each interstice being bounded by four webs, two, adjoining and connecting, webs of said four being arranged above the plane of the other two, substantially as set forth.

3. An integral screen-surface provided with substantially-quadrilateral interstices bounded by longitudinal and transverse webs, the alternate webs of each description being arranged in the plane of the working surface, while the remaining webs of each description are undulatory or sinuous in form, substantially as set forth.

This specification signed and witnessed this 26th day of July, 1898.

GEORGE W. CROSS.
